UNITED STATES PATENT OFFICE.

FRANK S. CLEGHORN, OF BROOKLINE, AND HARRY E. BARBER, OF BOSTON, MASSACHUSETTS.

SUPPORT.

1,175,707.

Specification of Letters Patent. Patented Mar. 14, 1916.

Application filed January 24, 1916. Serial No. 73,807.

To all whom it may concern:

Be it known that we, FRANK S. CLEGHORN and HARRY E. BARBER, citizens of the United States, and residents, respectively, of Brookline, county of Norfolk, and Boston, county of Suffolk, and State of Massachusetts, have invented an Improvement in Supports, of which the following description, in connection with the accompanying drawings, is a specification, like characters on the drawings representing like parts.

This invention relates to supports and particularly to supports designed to hold articles in an upright position.

15 The structure described herein is an improvement on that described by us in application No. 62,423, filed November 19, 1915.

While the support embodying the principles of our invention is adaptable to many 20 uses, we consider one of the most important of these that of maintaining radiators suspended adjacent the wall of a room.

In the accompanying drawing we have 25 shown a support designed for that use and for purposes of definiteness, we shall in the following description refer to a radiator support specifically as typical of our invention but it will be understood that in doing so our intention is to simplify the description and not to define or limit the principles of our invention.

30 Our invention will be best understood by reference to the accompanying drawings illustrating various specific embodiments of 35 our invention, wherein:

Figure 1 is a side elevation of a wall support for radiators embodying our invention, a part of a radiator being indicated in dotted lines; Fig. 2 is a top plan view of the 40 structure shown in Fig. 1; Fig. 3 is a side view of a portion of a modified form of support; Fig. 4 is a view of Fig. 3 as seen from the right; Fig. 5 is a view similar to Fig. 3 showing a still further modification; 45 and Fig. 6 is a front view of the attaching plate.

Referring now to Figs. 1 and 2, in which we have shown one form of support embodying our invention, we have there illustrated a support comprising a base portion or attaching plate 1 adapted to be screwed to a wall by any suitable means such as the

expansion bolt 2 on which the base plate 1 is preferably adjustable by means of the elongated slot 3. We prefer to provide for holding the plate in adjusted position positively as distinguished from frictionally. For this purpose we have here shown the plate 1 cast with teeth 1^a and a washer 2^a on the bolt provided with corresponding teeth. When the bolt 2 is screwed up the plate or base portion will be positively locked in its adjusted position. Extending from the base portion 1 is an arm or rest 4 which is adapted to hold suspended an article, such as the radiator A indicated in the figures. We have termed the part of this arm which engages the radiator a rest as it takes up the weight of the radiator. Extending from the arm 4 preferably at a point intermediate between the base portion 3 and the extremity of the arm is the supporting member 6 which in the modification shown forms with the arm an angular article-receiving holder. The radiator A is supported by the angular rest 4 and is held thereon by being clamped to the arm 6 at a location remote from the arm 4, that is, in a different horizontal plane therefrom. It should be understood that by the word "remote" we do not mean far distant in the ordinary sense as in fact we prefer to make the arm 6 relatively short and to clamp the radiator along a narrow zone near its base. The clamping mechanism employed we will 55 describe in more detail later. The support as described so far is similar to that disclosed in the application of Barber & Cleghorn above referred to, and by its use is obtained the same advantages that were therein referred to.

In the practical use of supports such as described, difficulties of adjustment arise. For example, in supporting heavy articles such as radiators, it is necessary to fasten the base plate 1 directly to the foundation wall of the house such as the brick wall, which is ordinarily covered by a finish. Such walls inevitably present minor irregularities or are slightly out of true and therefore the base plate 1 and the support may be disposed at a slight angle in spite of the small area of the former which minimizes this difficulty. If the radiator is mounted

on the rest and clamped against the supporting member 6, it will be disposed at this same angle and because of its large area the effect of a very slight deviation 5 from the perpendicular in the support will be very noticeable in the radiator and the job will look far from workmanlike.

The more particular object of our invention is to provide a support having all the 10 advantages of that described in the prior application referred to and on which an article may always be supported in a perfectly perpendicular position even although the base plate of the support itself is out of 15 plumb. Referring again to Figs. 1 and 2, it will be seen that we have there attained this object by providing a clamping means by which one can adjust and hold the radiator in any desired angular position relative to the arm 4 and the supporting member 6 so as to bring it into the exact perpendicular. These means include adjustable 20 abutments adapted to engage the opposite faces of the radiator and we have here shown them as comprising a screw or 25 threaded plug 7 threaded into the supporting arm 6 and having the conical head 8 which will fit in between the adjacent vertical pipes or so-called columns of the radiator. Tapped into this screw is a second screw 9 preferably provided with the 30 wedge shape washer block 10 journaled thereon which is adapted to engage between the radiator pipes on the other side. The 35 head 8 of the screw 7 has the ordinary slot 8' so that when the screw 9 is withdrawn the screw 7 can be manipulated from the right in Fig. 1. The advantages of our invention can now be understood by a brief 40 description of the operation of mounting a radiator on this particular form of support. Supposing the proper number of supports to be disposed in a horizontal line to receive the radiator, the latter is placed 45 thereon with each rest 4 taking in between adjacent upright pipes or columns of the radiator and engaging the horizontal connecting pipe between them. The screw driver or similar instrument is then inserted 50 between adjacent pipes from the outside with the radiator still in its place and the screw 7 is then adjusted to bring its conical head 8 against adjacent pipes of the radiator (at the left hand side in the figures). 55 The adjustment is such that when the radiator is pressed backward against the abutment formed by the screw it will be in a vertical position. The screw 9 is then inserted, still without disturbing the radiator, and 60 the radiator is clamped into place toward the supporting member 6 by means of the washer like head 10 which engages between the upright pipes of the radiator from the right hand side in the figures. The thread-

ed recess in which the screw 7 is mounted is 65 of such depth that it can entirely receive the screw 7 so that if necessary the radiator can be clamped by means of the screw 9 directly against the supporting member 6 as if the screw 7 were absent. 70

In Figs. 3 and 4, we have shown a portion of the support embodying a modified construction. Herein the two abutments which engage the article supported on opposite sides and clamp it between them are 75 separate. The screw 9^a with its washer block 10^a is threaded directly into the supporting arm 6 and acts in the same way as the screw 9 in Figs. 1 and 2. The other abutment is formed by an ordinary screw 7^a 80 entering the arm 6 at another location and having the large frusto-conical head 8^a, as shown. In these figures also we have shown a modification wherein the part of the arm of the supporting member 6 which carries 85 the screw 7^a is offset so that in the extreme of adjustment the head 8^a of that screw will lie flush with or inwardly of the surface of the supporting arm 6. It will be understood, however, that a separate screw 7^a 90 might be mounted in a recess much as is the screw 7 in the other modification. That is, the supporting member 6 would be dress faced as regards the screw 7^a. In using this form of the invention the block 10^a is turned 95 to bring its longer dimension in line with the space between the radiator pipes or columns. The radiator may then be placed on the support without removing the screw 9^a and the block 10^a then turned to the position shown in Fig. 2 to engage the radiator pipes. 100

In Fig. 5 we have shown an adjustable abutment 7^b and 8^b of the kind referred to wherein the screw 7^b is provided with a 105 shoulder 11 and has the wedge shaped washer block 8^b journaled thereon and held against movement by the shoulder 11. With this construction the block 8^b may be fitted between the pipes of the radiator 110 and give a movement of translation by the rotation of the screw 7^b without itself turning.

We have shown and described several 115 structures which illustrate the principles of our invention, but it is obvious that many other mechanical embodiments of the idea could be devised, whereby the angular relation between the base member and the article supported could be adjusted, and we 120 wish it understood that we consider what we have shown as typical only. By the use of our invention a strong and inconspicuous support which is practically hidden in use is provided and one on which it is very easy 125 to secure any given article since it is not necessary to handle the article itself a number of times or to make trials to determine

whether the proper adjustment has been attained. The article to be supported such as a radiator is simply placed on the support and immediately brought to its proper adjustment without further handling, the manipulation of the clamping means taking place from one side only of the support.

We have shown our adjusting mechanism as a part of one style of support of the type referred to in our prior application, but it will be understood that the general outlines of the structure can be considerably varied.

What we claim and desire to secure by Letters Patent is:

1. A wall support for radiators comprising, in combination an article-suspending bracket arm arranged to furnish a center of pivotal movement about the horizontal for the radiator and means carried by the support disposed to engage the radiator in a different horizontal plane from said rest to turn it on the support whereby to adjust the radiator to and hold it in a desired angular relation independently of the angular position of said support.

2. Supporting means comprising, in combination, a rest to hold an article against movement in a plane, an abutment adjustable transversely to said plane and disposed to engage the article at a point remote from said rest and a clamping device to retain the article against the abutment, said abutment and clamping device being manipulatable from the same side of said plane.

3. A device of the class described comprising, in combination, a base part, an article-suspending rest projecting therefrom, a supporting part extending transverse to said rest and in spaced relation to said base part and means carried by said supporting part remote from said rest to adjust the article to and hold it in a desired angular relation to said arm.

4. A device of the class described comprising, in combination, a base part, an article-suspending rest projecting therefrom, a supporting part extending transverse to said rest and in spaced relation to said base part, devices carried by said supporting part remote from said rest and individually adjustable toward and from said part and adapted to clamp the article between them.

5. A device of the class described comprising, in combination, an article-holding portion comprising two members defining an angle, one of said members constituting a rest and adjustable abutments arranged for engagement with opposite sides of an article carried by the other member at a location remote from the first member.

6. A device of the class described comprising, in combination, an article-holding

portion comprising two members defining 65 an angle, one of said members constituting a rest and adjustable abutments arranged for engagement with opposite sides of an article carried by the other member at a location remote from the first member, said 70 abutments being manipulatable from the same side.

7. A device of the class described comprising, in combination, an article-holding portion comprising two members defining 75 an angle, one of said members constituting a rest and screws carried by the other member at a location remote from the rest, said screws having tool receiving portions presented in the same direction and surfaces 80 adapted and arranged to engage as abutments opposite sides of the article held.

8. A device of the class described comprising, in combination, an article-holding portion comprising two members defining 85 an angle, one of said members constituting a rest, a recess in the other member, a screw housed in said recess and adjustable therefrom to form an abutment for the inner side of the article supported and a second screw 90 adapted to engage the outer side thereof and clamp the same toward said other member.

9. A device of the class described comprising, in combination, an article-holding portion comprising two members defining 95 an angle, one of said members constituting a rest, a screw carried by the other member and adapted to form an abutment for the inner side of the article supported and a second screw entering the first and adapted 100 to engage the outer side of the article and clamp it toward said other member.

10. A device of the class described comprising, in combination, an article-holding portion comprising two members defining 105 an angle, one of said members constituting a rest, a recess in the other member, a screw housed in said recess and adjustable therefrom to form an abutment for the inner side of the article supported and a second screw 110 entering the first and adapted to engage the outer side of the article and clamp it toward said other member.

11. A support for radiators comprising a rest to suspend the same, a member unitary 115 therewith and extending substantially parallel to the radiator at the rear thereof, members adapted to engage between adjacent pipes of the radiator at opposite sides thereof, adjustable toward and from said 120 member and accessible for adjusting manipulation between the pipes of the radiator from one side thereof, and means to secure the support to a vertical wall.

12. A support comprising a base member 125 for attachment to a vertical surface, an article receiving portion comprising a rest and a supporting member adapted respec-

tively for application to adjacent sides of an article supported means to clamp the article to said supporting member at a point remote from the rest, and means to adjust the angular relation to said base member of the article sustained by said rest and supporting member.

In testimony whereof, we have signed

our names to this specification, in the presence of two subscribing witnesses.
